NURSING NIPPLE

Filed March 17, 1928

Inventor
JOSEPH A. SMITH

By *Manuel C. Rosa*
Attorney

UNITED STATES PATENT OFFICE

JOSEPH A. SMITH, OF ATTLEBORO, MASSACHUSETTS

NURSING NIPPLE

Application filed March 17, 1928. Serial No. 262,411.

My invention relates to an improved nursing nipple characterized in that the nipple is non-collapsible and does not descend into the neck of the nursing bottle.

5 It is a familiar fact that the ordinary nursing nipples of commerce possess the undesirable feature of collapsing in use due to the partial vacuum which by the sucking of the infant is created, all to the annoyance and disturbance of the infant who is generally made fretful thereby. Another evil to which the nipples now in use are subject arises after the nipple becomes extremely flexible from use so that it is thrust down the neck of the 10 nursing bottle with facility by the infant. Both these evils do much to deprive the infant of a portion of the pleasure which generally accompanies feeding.

Many attempts have been made to solve 20 the problem presented by the evils specified and in fact many forms of nipples have been proposed and patented but none has as yet met with universal acceptance as accomplishing the sought for result.

25 It is an object of my invention to provide a nursing nipple, simple in design and effective in operation which permits the uninterrupted flow of fluid to the infant.

A further object of my invention is to provide 30 an improved nursing nipple wherein the interior walls of the expandable socket are provided with a rib member running from the rim of said socket to a point substantially adjacent the shoulder portion of the socket, 35 said rib being provided at its innermost point with a projection which is adapted to overhang the mouth of the bottle neck, said rib member subserving the double purpose of preventing the formation of a partial vacuum 40 within the nipple head and preventing the nipple top from being pushed into the neck of the bottle.

A still further object of my invention is to 45 provide a non-collapsible nursing nipple of such a design as to be fool-proof, the interior wall of the expandable socket being provided with vertical ribs extending to a point adjacent the shoulder portion of the nipple, 50 said interior wall being further provided with protruding segments circumferentially

disposed within the socket which are adapted, of themselves as well as in conjunction with the protruding ends of the ribs, to engage the mouth of the bottle and thereby act as stop members to prevent the nipple from being pulled too far down on the bottle neck. 55

Other objects and advantages will appear from the following detailed description.

This invention is an improvement on the nursing nipple described and claimed in Patent Number 1,653,787 of which I am the patentee. 60

I attain these objects by the nipple illustrated in the accompanying drawings wherein:

65 Figure 1 is a cross sectional view taken through my improved nipple showing the vertical ribs and the circumferential segments integrally formed with the socket.

70 Figure 2 is a view showing the nipple applied to a nursing bottle, the nipple and bottle neck being shown in cross section for the sake of greater clarity.

75 Figure 3 is a view taken along line A—A of Figure 1 in the direction of the arrows showing the manner in which the protruding portion of the rib members and the segment members overhang the mouth of the bottle.

80 Figure 4 is a view of a modification showing a nipple wherein two opposed rib members are employed within the nipple socket, the protruding tips of said ribs being aligned.

85 Figure 5 is a view taken along line B—B of Figure 2 showing the air ducts formed by the integral ribs.

90 Figure 6 is a view of another modification showing the use of two segments within the nipple socket adjacent the shoulder portion which act to prevent the nipple from being pulled too far down on the bottle neck as well as preventing the nipple top from being pushed into the bottle.

95 Similar numerals refer to similar parts throughout the several views.

100 Referring to the drawings, 1 designates the bead on the nursing nipple, 2 the expandable socket which is generally of a lesser diameter than the neck of the bottle to ensure a close fit, 3 the shoulder portion of the socket, 4 the closed end or nipple proper, 5 the hole in the

extremity of said closed end for the egress of the fluid.

So far as the exterior of the nipple itself is concerned, the structure is unchanged. I

5 have found that in the manufacture of the ordinary nipple that it is easily possible, without entailing any further material expense, to mould into the interior of the expansible socket an integral vertical rib member 6

10 which extends from the base portion of the bead to the shoulder portion of the socket, the rib member 6 being sufficiently set off from the remainder of the socket wall as to cause the formation of small air ducts or pas-

15 sages when the socket is placed on the mouth of the bottle. However, in view of the fact that the utility of the air ducts would be nullified if only a straight rib were used, since by pulling the nipple down too far on the

20 bottle neck the inner extremity of the rib would descend below the mouth of the bottle.

I have found that by providing a lug or projection 7 at the inner extremity of the rib 6 that in so doing the overhanging projec-

25 tion serves to act as a stop member. A fur-ther function of the overhanging projection is that it acts as an obstruction to prevent the nipple top from being pushed into the bottle. Although I have shown a nipple em-

30 ploying two rib members with overhanging portions it is to be understood that a nipple may be provided with only one rib member of the character described. I do not wish to be limited to any particular number of rib 35 members as the number may be varied as the need arises. In Figure 4 there is shown a nipple provided with two opposed rib members together with outwardly projecting lugs or ends which overhang the bottle mouth.

40 Referring to Figure 3 it will be seen that the vertical integral ribs 6 acts as spacers or buffers between the side of the bottle neck and the remainder of the socket wall whereby air ducts, shown at 8, are formed. These air

45 ducts are continuous from the bead of the socket to the interior of the nipple by reason of the extent of the rib which renders pos-sible the continuity of the air passage at all times during the feeding of the infant. The

50 size and extent of the air ducts may be varied according to the thickness and width of the rib members. The amount of air allowed to enter through these small ducts or passages is sufficient to counteract any tendency with-

55 in the nipple proper to form a partial vacu-um. The distance or extent to which the lugs 7 project within the interior of the sock-et 2 may be varied, however, a size sufficient to prevent the nipple from being pulled too 60 far down as well as preventing the entry of the nipple within the mouth of the bottle should be employed.

An auxiliary feature which may be em-ployed to further reinforce the nipple as well 65 as to act as additional stop members are the

segments or lugs 9 which are disposed along the interior wall of the socket 2 in substantial alignment with the lugs 7 by not contacting the same. These segments are integrally formed with said socket wall and may be 70 made of any desired configuration. The seg-ments may or may not be used, however, if used alone they serve the purpose of acting as stop members to prevent the nipple from being pulled down too far as well as pre-75 venting the nipple top from being pushed into the bottle.

Referring to Figure 2 there is shown a 80 nipple applied to the neck 10 of the bottle 11, the lugs 7 and segments 9 overhanging the 85 mouth 12 of the bottle, the vertical ribs 6 be-ing shown between the neck of the bottle and the wall proper of the expansible socket.

In view of the fact that the rib members 85 with their lug portions as well as the seg-ments may be made integral with the nipple they may be made of the same material of 90 which the nipple is made and in fact may be made in the same operation, the only differ-ence being a mould designed to produce the 95 desired configuration within the interior of the expansible socket.

The mode of use of my improved nipple is 95 apparent from an inspection of the drawings and indeed is no different from the nipples 95 now in use on the market as it is intended to be applied to the bottle in the same way.

All that has been said above in the descrip-tion of my preferred embodiment is offered 100 by way of illustration and not limitation. I do not wish to be limited to the exact struc-ture of the preferred embodiment shown and described, or to any particular material used 105 in the construction of parts, or to the design of parts, but desire protection as against any variations in structure or substitution of equivalents which utilize the principle of my invention and fall within the purview of my invention and are within the spirit and scope 110 of the following claims:—

The invention having been set forth, what is claimed as new and useful is:

1. An elastic nursing nipple for use on a 115 bottle neck comprising in combination a socket member, a top portion, said socket member having a substantially vertical rib member disposed on its interior, said rib member extending from the base of said socket member a sufficient distance within 120 said socket member to extend beyond the mouth of the bottle, means within said socket member and substantially aligned with the inner extremity of said rib member for en-gaging the mouth of the bottle whereby the inner extremity of said rib member is not 125 pulled below the mouth of the bottle, said rib member being adapted to form air ducts between the bottle neck and the socket mem-ber.

2. In combination with an elastic nursing 130

nipple having a top portion, a socket member, duct forming means disposed within said socket, said duct-forming means extending from the base of said expandible socket a substantial distance along the interior wall of said socket member, and a stop means attached to said interior wall in substantial alignment with the inner extremity of said duct-forming means, said stop means being adapted to abut against the mouth of a bottle during use of said nipple.

3. An elastic nursing nipple for use on a bottle neck comprising a socket member, a top portion, rubber lugs integral with said socket member and disposed a substantial distance within the interior of said socket member, said rubber lugs projecting inwardly and being adapted to overhang the mouth of a bottle, to prevent the nipple from being pulled too far down on the bottle neck.

4. An elastic nursing nipple for use on a bottle neck comprising in combination a socket member, a top portion, said socket member having a substantially vertical rib member disposed on its interior, said rib member being integral with said socket member and extending from the base of said socket member a sufficient distance within said socket member to extend beyond the mouth of the bottle, means within and integral with said socket member, said means being substantially aligned with the inner extremity of said rib member for engaging the mouth of the bottle whereby the inner extremity of said rib member is not pulled below the mouth of the bottle, said rib member being adapted to form air ducts between the bottle neck and the socket member.

5. In combination with an elastic nursing nipple having a top portion, a socket member, elastic duct-forming means disposed within and integral with said socket, said duct-forming means extending from the base of said expandible socket a substantial distance along the interior wall of said socket member, and elastic stop members disposed within and integral with said socket member in substantial alignment with the inner extremity of said duct-forming means, said stop members being adapted to abut against the mouth of a bottle during use of said nipple, said elastic duct forming means and elastic stop members being of the same material as that constituting the nursing nipple.

Signed at Fall River in the county of Bristol, State of Massachusetts this tenth day of March, 1928.

JOSEPH A. SMITH.
